Patented July 11, 1972

224,228

FRACTIONAL HORSEPOWER DC CONTROLLER

Daniel M. Flynn, Hampden, Stanley J. Bandoski, Jr.,
Springfield, and William R. Clow, Agawam, Mass.,
assignors to Hampden Engineering Company, East
Longmeadow, Mass.

Filed July 27, 1970, Ser. No. 24,154

Term of patent 14 years

Int. Cl. D13—03

U.S. Cl. D26—13

Fig. 2

Fig. 3

Fig. 4

Fig. 5

Fig. 6

Fig. 7

FIG. 1 is a front elevational view of the fractional horsepower DC controller.

FIG. 2 is a reduced scale top view.

FIG. 3 is a reduced scale left-hand end elevational view.

FIG. 4 is a reduced scale front elevational view with certain elements and indicia omitted due to their illegibility in extremely small scale reproduction.

FIG. 5 is a reduced scale right-hand end view.

FIG. 6 is a reduced scale bottom view.

FIG. 7 is a reduced scale rear view.

We claim:

The ornamental design for a fractional horsepower DC controller, as shown and described.
